UNITED STATES PATENT OFFICE.

JAMES B. FRENCH, OF JAMAICA, NEW YORK.

TRANSFER OR FLOAT BRIDGE.

1,279,316.

Specification of Letters Patent. Patented Sept. 17, 1918.

Application filed July 3, 1918. Serial No. 243,190.

To all whom it may concern:

Be it known that I, JAMES B. FRENCH, a citizen of the United States of America, residing at Jamaica, Long Island, in the county of Queens and State of New York, have invented certain new and useful Improvements in Transfer or Float Bridges, of which the following is a specification.

My invention relates to transfer bridges, over which railroad cars are passed from their floats to land, or vice versa, and the object of my invention is to provide a support to span the gap which occurs between the bridge rails and float rails under various conditions of tide, loading and unloading, and thus not only to prevent derailment of the cars at this point, but also to protect the rail ends and adjacent parts against injury.

20 In the accompanying drawings,

Figure 1 is a plan view of the juxtaposed ends of a car float and transfer bridge to which my invention is applied in one form;

Fig. 2 is an end elevation of the bridge;

25 Figs. 3 and 4 are longitudinal sections through the toggle bolt in different positions;

Fig. 5 is a side elevation of the rail extension device and associated parts;

30 Fig. 6 is an end elevation thereof;

Figs. 7 and 8 are side elevations thereof, showing the bridge in different angular positions with relation to the float and showing the rail extension in operative position.

35 In their general characteristics the float 10 and transfer bridge 11 are of common construction and have laid thereon the usual track rails 12, 12^a for the cars and guard rails 13, 13^a adjacent thereto. As shown in

40 Fig. 1, the float 10 has been drawn to and is held in car-discharging or receiving position by the usual mooring winches 14 and cables 15. In order to maintain in register the ends of the tracks on the float and

45 bridge, it is customary to provide on the bridge, heavy toggle bars 16 which slide in guide pockets 17 and take into coöoperating pockets 18 on the float. Should the rails still fail of precise alinement after the tog-

50 gles have been engaged with the pockets on the float, the rails on the bridge may be shifted transversely by means of a rail adjuster 19. Even after these adjustments have been made, however, the rail ends on

55 the float and bridge are not necessarily brought to precisely the same elevation, par-

ticularly if the toggle fittings and rail ends have become worn or distorted through use, and, in any event, these adjustments do not prevent a considerable opening or gap between the rail ends when the tidal conditions are such that the bridge must be inclined.

It is the purpose of the present invention to reduce the bad effects of this difference in elevation of the rail ends and to bridge the gap or opening between them by the introduction of rail extension pieces 20, which, after the float has been moored and toggled and the bridge rails adjusted, if necessary, can be extended to span the gap, and, after the passage of the cars has been completed and the float is about to be released, can be withdrawn. In order that these rail extension pieces 20 shall not be damaged or cause damage to the float or to the bridge, it is highly desirable, if not actually necessary, that they shall not remain in extended position when the float is not toggled to the bridge, and I have provided, therefore, an interlocking arrangement to prevent the advancement of the rail extensions 20 until after the toggles have been advanced and to prevent the withdrawal of the toggles until after the rail extensions have been withdrawn.

The rail extension pieces 20, as here shown, comprise bars, the bodies of which are of inverted-T-shape (Fig. 6) lying closely adjacent the outer faces of the track 90 rails 12, so that the head of the rail overlies the shoulder of the bar on one side, while the top of the latter lies beside and at substantially the level of the rail head. An anchor rail 21 lies against the opposite side 95 of the bar 20 with its head overlying the shoulder on this side. Both track rail 12 and anchor rail 21 are fastened to a plate 22 which is free to slide transversely on the operation of the track adjuster 19, and are tied together by a cross bolt 23 which passes through a slot 24 in the rail extension 20 and thus limits the longitudinal movement of the latter. At its forward end the rail extension has a nose piece 25 which is so 100 shaped on its lower face as to clear the fastenings which hold down the rails on the float, while its upper face is so shaped that the treads of the car wheel strike it as favorably as possible at the various angles at 105 which it is presented in the positions which it must assume, due to the inclinations of

the bridge at different tides and different stages of the loading and unloading operations. (See Figs. 7 and 8.) In the form here shown, the nose 25 of the rail extension 5 is more or less wedge-shaped, the upper face being downwardly inclined from the plane of the rail and the lower face being upwardly inclined. It is obvious that, as the weight of the car is imposed upon the nose 10 25, the rail extension acts as an anchored cantaliver or bracket.

In order to prevent the rail extension from being driven from operative position when struck by the car wheels, I provide, 15 at its rear end, an offset arm or lug 26, against which bears the latch 27 freely pivoted in the brackets 28 and lying out of the way below the rail head in both operative and inoperative positions (Figs. 5 and 8).

20 The interlocking arrangement, which prevents the advancement of the rail extension 20 before the toggles 16 have been advanced or the retraction of the toggles until the rail extensions have been retracted, is secured by an interlocking bar 29. This bar extends transversely of the bridge beneath the rails and carries, on the one hand, pawls 30 engaging the toggles 16, and, on the other hand, a locking plate 31 engaging a downwardly offset shoulder 32 on the rail extensions 20. When the toggles are withdrawn (Fig. 3), the pawls 30 are engaged by the lower face of the toggles, and the bar 29 cannot be rotated, and since this rotation is necessary in order to bring the locking plate 35 31 out of engagement with the shoulder 32 of the rail extensions 20, the latter cannot be advanced. When the toggles 16 are advanced, however, the longitudinal slots 33 therein 40 are brought above the pawls 30 and the bar 29 is therefore now free to be rotated and the rail extensions 20 advanced. The shoulder 32 is of such extent, however, that, when the rail extensions are advanced (Figs. 7 45 and 8), it overlies the locking plate 31 and prevents the rotation of the locking bar 29. Consequently, the toggles 16 cannot now be retracted, since the ends of the slots 33 impinge against the pawls 30 and are thus 50 halted until the rail extension pieces 20 have been retracted to the position shown in Fig. 5, thus freeing the locking plate 31 so that the locking bar 29 can now be again rotated in the reverse direction and the toggles retracted.

60 All of the parts—viz., the toggles 16, the rail extensions 20, and the latches 27—are operated by means of a bar in the hands of the attendant or by the foot, and the parts 65 are ruggedly constructed to this end and for the rough service to which they are subjected. It will be obvious that the details of arrangement and construction are merely illustrative and may be varied in many ways without departing from what I claim as my

invention. Moreover, while they have been shown as applied to a particular use, the invention may be adapted to various other conditions to which the general arrangement and relation of parts are suitable.

70 I claim:—

1. In a car transfer bridge, a car rail, and a longitudinally shiftable rail extension piece lying wholly to one side thereof but associated therewith and projecting, in operative position, beyond the end of the car rail to span the gap between said rail and the coöperating rail of a car float and serving to support the car wheels as they pass from the float rail to the bridge rail. 75

2. In a construction such as specified in claim 1, a rail extension piece having only at its forward gap-spanning end a wheel-supporting surface inclined to the plane of the bridge rail. 80

3. A car transfer bridge having different inclinations under different tidal conditions and having a car rail extending substantially to the end of the bridge to coöperate with the rail of a juxtaposed car float, 90 means to hold said float in juxtaposition to the bridge, and a rail extension piece associated with the bridge car rail and projecting, in operative position, beyond the end of the bridge to span the gap between the car rail thereon and the coöperating float rail when the bridge is upwardly inclined, the gap-spanning portion of the extension piece being inclined to approach the horizontal in this position of the bridge. 95

4. A car transfer bridge having different inclinations under different tidal conditions and having a car rail extending substantially to the end of the bridge to coöperate with the rail of a juxtaposed car float, 105 means to hold said float in juxtaposition to the bridge, and a rail extension piece associated with the bridge car rail and projecting, in operative position, beyond the end of the bridge to span the gap between the car rail thereon and the coöperating float rail when the bridge is upwardly inclined, the gap-spanning portion of the extension piece being inclined to approach the horizontal in this position of the bridge, together with 110 means for retracting and extending said extension piece parallel to the rail and means for holding the same in both retracted and extended positions.

5. In a car transfer bridge, a car rail, 120 and a rail extension piece associated therewith projecting, in operative position, beyond the end of the car rail to span the gap between said rail and the coöperating rail of a car float and serving to support the car 125 wheels as they pass from the float rail to the bridge rail, in combination with means on said bridge to engage the car float and hold the same in predetermined position with relation to the bridge, and means in- 130

terlocking said rail extension piece and float-engaging means to insure predetermined sequence in the operation thereof.

6. In a car transfer bridge, a car rail, 5 and a rail extension piece associated therewith projecting, in operative position, beyond the end of the car rail to span the gap between said rail and the coöperating rail of a car float and serving to support the car 10 wheels as they pass from the float rail to the bridge rail, in combination with means on said bridge to engage the car float and hold the same in predetermined position with relation to the bridge, and means in 15 interlocking said rail extension piece and float-engaging means to prevent the actuation of said rail extension piece until the float-engaging means have been operated.

7. In a car transfer bridge, a car rail, 20 and a rail extension piece associated therewith projecting, in operative position, beyond the end of the car rail to span the gap between said rail and the coöperating rail of a car float and serving to support the car 25 wheels as they pass from the float rail to the bridge rail, in combination with means on said bridge to engage the car float and hold the same in predetermined position with relation to the bridge, and means interlocking said rail extension piece and float-engaging 30 means to prevent the withdrawal of the latter until the rail extension piece has been withdrawn from operative position.

8. In a car transfer bridge, a car rail, 35 and a rail extension piece associated there-

with projecting, in operative position, beyond the end of the car rail to span the gap between said rail and the coöperating rail of a car float and serving to support the car 40 wheels as they pass from the float rail to the bridge rail, in combination with means on said bridge to engage the car float and hold the same in predetermined position with relation to the bridge, and means interlocking said rail extension piece and float-engaging 45 means to insure the actuation of the latter in advance of the rail extension piece and the withdrawal of the float-engaging means after the retraction of said rail extension piece. 50

9. In a railroad bridge, a track rail, a rail extension piece associated therewith and longitudinally displaceable with relation thereto to bridge the gap between said bridge rail and a coöperating rail, engaging 55 means to hold said rails in alinement, and means interlocking said engaging means and rail extension piece to insure their operation in predetermined sequence.

10. In a car transfer bridge, a rail extension piece longitudinally shiftable to overhang the end of the bridge, means to hold said rail extension piece in its advanced position, and structural means holding said rail extension piece to the bridge 60 and affording a cantaliver anchorage therefor. 65

In testimony whereof I have signed my name to this specification.

JAMES B. FRENCH.
